INWARDLY OPENING BREECH CLOSURE FOR
ROCKET LAUNCHER

William E. Good, Riverton, N. J., assignor to the United States of America as represented by the Secretary of the Army

Application April 21, 1952, Serial No. 283,383

4 Claims. (Cl. 89—1.7)

The present invention relates to an inwardly opening breech closure for a rocket launcher. More particularly, the invention relates to an inwardly opening, non-fouling breech closure for a rocket launcher which protects the breech sealing surface from excess carbonization and which enables the launcher to be easily loaded.

The use of open-breech launchers is not permissible under certain conditions, particularly for example in tank turrets, where the rearward discharge of propellant gases into the occupied, inclosed turret would result in contamination of the inclosed air to an extent to seriously impair the efficiency of the tank crew.

The closed breech rocket launcher was developed with a view toward preventing the backward discharge of propellant gases into the inclosed space, while at the same time enabling the weapon to achieve an increased range due to the thrust assist exerted upon the rocket by the gas exhaust.

The character and functioning of breech mechanisms for closed breech launchers present many problems which require solution for the satisfactory and efficient operation of the launcher. Previous mechanisms developed for the operation of the breech closure were found to be cumbersome and unwieldy, involving rack and pinion arrangements, pulleys, gearing and other such similar devices for sliding or moving the closure. Even a more serious objection was the inability to effectively develop a closure which remained gas tight under all conditions of firing, consequently leakage of gas about the closure oftentimes resulted in the carbonization and fouling of the various parts, including the breech sealing surfaces, with the consequent reduction in operating efficiency of the launcher.

It is accordingly an object of this invention to provide a quick, inwardly opening breech closure for a rocket launcher which is free of the defects noted in other breech closures.

It is also an object of this invention to provide a rocket launcher which is quickly and easily loaded, positive and safe in its operation, and substantially free of excess carbon deposit.

It is also a further object of this invention to provide a rocket launcher having an easily operated breech closure in which the rearward force of the propellant gas augments sealing action to effectively seal the launcher tube against the rearward discharge of propellant gases and to direct such gases forwardly out of the muzzle portion of the tube.

It is also a further additional object of this invention to provide a launcher having a breech closure which is relatively simple, easy to construct, easy to operate, positive in the nature of the seal provided against the escape and leakage of propellant gases, and which makes it possible to easily clean the inner gun parts which have been exposed to carbonization from such gases.

Still another object of this invention is to provide a hinged, inwardly opening breech closure for a rocket launcher which is provided with mechanical means

2

mounted externally of the breech assembly to operate the closure, and additional hydraulic means for accomplishing the same purpose.

With these and other objects in view, which will become apparent as the following specification develops, reference is made to the accompanying drawing forming a part of the specification and wherein:

Figure 1 is a side elevation of a rocket launcher showing the operating mechanism for the breech closure.

10 Figure 2 is a vertical longitudinal section of the rocket launcher.

Figure 3 is a view in elevation of the breech end of the rocket launcher.

15 Figure 4 is a transverse section taken on line 4—4 of Figure 2.

Figure 5 is an end elevation of a modification of the breech closure looking to the right in Figure 6.

Figure 6 is a section taken on line 6—6 of Figure 5.

20 Figure 7 is a top view of the toggle linkage as seen in Figure 1.

Figures 8 and 9 are diagrammatic views of the hydraulic system and valves for opening and closing the breech door.

25 Referring to the drawing wherein like reference characters have been used to designate the same parts in the various figures, 1 identifies a cylindrical rocket launcher tube provided with four parallel sheet metal launcher rails 2 (2 seen in Figure 2) equally angularly disposed about the inner wall of tube 1 and extending forwardly to the muzzle 3 of the launcher tube. The rear end of the launcher tube is provided with an outwardly directed flange 4 to which is bolted or secured in any conventional manner a bulbous enlargement or ball 5 to be received in the ball socket of the launcher mount (not shown). Ball 5 is provided with a central opening 6 in axial alignment with launcher tube 1, and peripherally disposed about opening 6 on the flat rearward face of ball 5 is a flange 7 of a housing assembly 8 and which is removably bolted to ball 5.

30 40 Breech housing assembly 8 is substantially elongated rearwardly of enlargement 5 to provide sufficient space for accommodating the inwardly opening breech closure, and in the exemplification illustrated the lower major portion 9 of the housing 8 is cylindrical in shape, merging as at 10 with an upper rectangular portion 11. The lower wall 12 of cylindrical portion 9 is flattened as at 13 to provide a lower limit for housing 8 in longitudinal alignment with the lowermost inner surface of tube 1, whereas the upper wall 14 of rectangular portion 11 is elevated 45 above the top surface of tube 1 to an extent to permit a rocket inserted into the breech opening to clear the breech closure when the closure door has been swung inwardly and upwardly as later to be described. The forward portion of wall 14 is inwardly and downwardly inclined as at 15 and is bolted by its flange 7 to ball 5.

50 55 The rear end of upper wall 14 has a downwardly struck portion or flange 16, and similarly lower wall 12 is provided with an upwardly directed flange 17, both flanges 16 and 17 cooperating to provide a rear wall 13 for housing 8 having formed therein a circular opening 19. A breech ring or plate 20 having a circular opening 21 is bolted as by bolts 22 to the rear wall 18, opening 21 being further defined by a forwardly directed flange or lip 23 integral with the main body portion of plate 20, and circumferentially engaging on its outer surface as at 24 the periphery of wall 18 encompassing opening 19. The inner edge of lip 23 is provided with a conical seating surface 25 which is adapted to be sealingly engaged by a gate or breech closure 26 having a peripherally conical surface 26a to mate with conical surface 25 of the breech ring.

60 65 70 75 80 85 90 95 Breech closure 26 is provided with a forwardly ex-

tending reduced portion 27 having a flat forward face 28 against which is superimposed a flat metal bar 29 of substantial width and thickness which forms a shaft for swinging the breech block or closure 26. Shaft 29 and closure 26 are secured together by means of a nut 30 received in horizontally aligned holes 31 and 32 in the shaft and door respectively, capped by a bolt 33 disposed in a shallow cavity 33a formed in the rear face of the breech block.

The support structure for actuating the breech block (as seen in Figure 4) comprises opposed adjustable cone pointed trunnions 34 and 35, one of which 35, is journaled in bearing 37 formed in the right side of rectangular portion 11 of housing 8. Both trunnions 34 and 35 extend inwardly to be received in conical pockets 38 and 39 formed in opposed sides of upwardly extending portion 29a of shaft 29. A pin 39' fixes trunnion 35 to shaft 29.

The mechanical means for actuating the breech block is connected to trunnion 35 which is the driving trunnion, mounted on the right of housing 8 as seen in Figures 1, 3, 4 and 7. The mechanism is formed as a toggle link arrangement 40 comprising a first vertical link or arm 41 (see Figure 1), fixedly secured to driving trunnion 35 on its upper end as at 42, and having a pivotal connection 43 on its lower end with a horizontal link 44, which in turn is connected for pivoting as at 45 with a second horizontal link 46. Horizontal link 46 is pivotally connected to a stud 47 which protrudes from and is secured to the side of the breech housing as seen at 47a (see Figure 7). Thus when a force is exerted upwardly against link 46, as seen in Figure 1, the link will pivot clockwise about pivotal connection 47, carrying with it, horizontal link 44, which in turn will force vertical arm 41 in a counterclockwise direction, due to pivotal connections 45 and 43. As a result breech closure door 26 is swung inwardly and upwardly approximately 90°, the thickness of the door being such that sufficient clearance is provided to permit the insertion of a rocket into place through the circular opening in the breech housing and onto the launcher rails. (See Figure 2.) In order to conveniently operate the toggle mechanism a downwardly and rearwardly extending operating lever 48 (see Figure 1) is bolted or secured in any well known manner to link 46, and secured to the lever is a handle 49, which when not in use is folded into place upon lever 48 (see Figure 7), but which may be grasped and unfolded when it is desired to swing the breech block open. The linkage arrangement is easy to operate and provides a large mechanical advantage to insure proper seating of the conical sealing surfaces of the breech block in the closed position.

A brass obturator ring 50 (see Figure 2) encircling reduced forward portion 27 of closure 26, and having a larger diameter thinner portion 51 is positioned against the forward surface of breech ring 20 to span the joint made by conical surfaces 25 and 26a when the door is closed, thereby protecting the sealing surfaces from direct exposure to the hot propellant gases. As can readily be seen the structure provided makes it apparent that when a rocket is fired the rearward force exerted by the rocket discharge acts to force the breech block into intimate contact with the conical sealing surface of the breech ring.

Figures 5 and 6 illustrate a modified construction of the breech block assembly wherein a brass split ring and a composition obturator pad provide for more intimate sealing between the block and breech ring. The construction permits greater latitude in manufacturing with increased tolerances, and comprises a breech block 100 which is a substantially thick metal member having a rounded extreme peripheral edge 101 merging into a rearwardly directed conical sealing surface 102 to engage the mating conical sealing surface 103 of a breech ring 104 secured to the breech housing (not shown) in any convenient manner. In order to insure better sealing

between the block breech ring, the block is provided with a first rearward reduced portion 105 forming a recess with surface 103 for receiving a ring shaped obturator pad 106 of rubber composition or the like adapted to engage the peripheral surface of conical surface 103 of the breech block. Rearward of reduced portion 105 is a second further reduced rearwardly extending portion 107 about which is disposed a split brass obturator ring 108 also shaped to intimately contact the surface 103.

10 The cooperation between the breech block, obturator pad, obturator ring and breech ring provides a gas tight fit which prevents leakages and carbonization of the conical sealing surfaces. The breech block is provided with a central aperture 109 to receive a bolt 110 for securing the block to an operating shaft 100a. The breech block is also provided with a plurality of longitudinal circumferentially disposed holes 111 radially inwardly of the outer radius of reduced portion 105. Within the holes 111 are disposed adjusting screws 112 which extend from the rear flat surface inwardly to a point midway of the front surface of the breech block. The screws in turn abut longitudinal pins 113 which are received in the remaining portions of holes 111, and which have ends 114 extending outwardly beyond the forward surface of block 100 to contact the rear surface of operating shaft 100a. The adjusting screws 112 may be turned to angularly adjust the block 100 with respect to shaft 100a in order to take up any clearance and thereby insure a gas tight fit between the block and the brass ring when the block is in fully closed position.

15 In addition to the mechanical means for operating the toggle mechanism, hydraulic means may also be provided as seen in Figures 1, 8 and 9. The hydraulic mechanism comprises a hydraulic cylinder 115 lying rearwardly of operating lever 100a and pivotally connected to the breech housing as at 116 (see Figure 1). A piston 117 tightly engaging the walls of and reciprocable in cylinder 115 has secured to one face thereof an operating rod 118 which extends outwardly through a hole 119 in the rear face 120 of the cylinder (as seen in Figure 8). Rod 118 has a pivotal connection 121 with link 46 at a point forwardly of the connection made by operating lever 48 with link 46. The hydraulic system (see Figures 8 and 9) comprises a flow control and pressure metering valve 45 122 having a conduit connection 123 to a high pressure oil supply (not shown). The metered oil supply flows out of metering valve 122 by way of a conduit 125 and into a manually operable valve 126 for controlling the flow of hydraulic fluid to hydraulic cylinder 115. Valve 126 is provided with fluid outlets 127, 128 and 129, outlet 127 being connected to chamber 130 in cylinder 115 rearwardly of piston 117 by way of conduit 131, outlet 128 in like manner being connected to a chamber 132 forwardly of piston 127 by way of conduit 133, and outlet 129 being connected to exhaust by way of conduit 134. Valve 122 is provided with a manually operable rotating plug 135 having a diametral passage 136, a first passage 137 parallel thereto and radially outwardly on one side thereof, and a similarly parallel passage 138 on the opposed side thereof. Referring to Figure 9, when it is desired to operate the breech closure manually, rotor 135 is turned to position 2 so that passage 136 connects outlets 127 and 128. In this position no hydraulic pressure is admitted to either chambers 130 and 132 of the hydraulic cylinder and rod 118 and piston 117 are free to reciprocate as the quadratic toggle linkage is mechanically actuated to swing the breech block open or closed. Position 1 illustrates the position of the rotor plug when it is desired to open the breech. In this position passage 137 connects pressure supply in conduit 125 to outlet 127 and then by way of conduit 131 to chamber 130 to move the piston forwardly (as seen in Figure 8), also chamber 132 is connected to exhaust conduit 134 by way of conduit 133, outlet 128 and passage 138. When it is desired to close the breech opening, the rotor is turned

to position 3 to connect chamber 132 to pressure supply conduit 125 by way of passage 137, outlet 128 and 133; chamber 130 in turn being connected to exhaust conduit 134 by way of conduit 131, outlet 127 and passage 138. In both positions 1 and 3 of the rotor plug as can readily be seen, passage 136 is in neutral position, and is not in communication with any of the pressure outlets or conduits.

In Figure 6, numeral 140 identifies one of a series of six equiangularly spaced pins each having an identical mounting. As shown in this figure, each pin is slidably mounted within aligned apertures in block 100 and obturator ring 108. The aperture in block 100 is enlarged to receive a head 140a formed upon the pin and a spring 141 surrounds the pin and urges it forwardly to urge the block and ring together in a manner obvious from inspection of the figure. As there is a slight clearance between the ring and block, the described construction operates to compress pad or gasket 106 to effect a gas-tight seal when the breechblock is closed. This result may be augmented by so forming and disposing the parts that the frusto-conical surface on ring 108 engages surface 103 a little before the corresponding surface 102, to thereby effect a gas-tight seal. A cap screw 142 is threaded into the enlarged forward portion of the bore accommodating each pin 140 to protect the same from the rocket gases.

The foregoing specification and drawings illustrate and exemplify preferred embodiments of a quick opening, manually or hydraulically operable breech closure device, which is positive in its sealing action and which uses rocket discharge pressure to insure more intimate contact between the sealing surfaces. Numerous other modifications and alterations of the illustrated structures will be apparent to one skilled in the art, and it is obvious that the same may be made without departing from the spirit and scope of the invention as defined in the following claims.

I claim:

1. In a rocket launcher, an elongated cylindrical launcher tube having a circumferentially flanged rear end, a breech housing secured to said flanged end and comprising side, bottom and top walls defining a breech space, and a rear wall having an opening formed therein, a breech ring removably fixed to the outer surface of said rear wall about said opening and comprising an inwardly directed reduced portion peripherally engaging the wall of said opening with a tight fit, there being a breech opening formed in said reduced portion having an oblique wall defining a conical seat, an inwardly opening rearwardly stepped breech block swingable to close said breech opening, said breech block having a first inner portion having a conical peripheral surface to engage the inner portion of said conical seat with a tight fit, a middle portion of slightly reduced diameter, and an outer portion again reduced in diameter to provide a recess, there being a metal obturator ring received in said recess having a resilient connection with said breech block, said obturator ring having a conical peripheral surface to engage the outermost portion of said conical seat, a toroidal resilient obturator pad surrounding said middle portion of slightly reduced diameter having inner and outer surfaces tightly abutting corresponding opposed surfaces of said breech block and obturator ring respectively, and having an outer peripheral surface adapted to tightly engage a middle portion of said conical seat to provide a gas tight seal, an operating arm mounted in said breech space for swinging said breech block open or closed, and comprising a flat bar having one end secured to the inner surface of said breech block 70

and the other end provided with opposed pockets for receiving inwardly directed diametrically opposed trunnions mounted in the side wall of said breech housing, one of said trunnions forming a driving trunnion actuable by a toggle link mechanism for swinging said breech block, said link mechanism comprising a first link having one end secured to an end of said driving trunnion protruding from said side wall, a second link having one end pivoted on the outer surface of said side wall, a third link having one end connected to the free end of said first link, and the other end connected to the free end of said second link, and means engaging said second link adjacent said free end operable to actuate said mechanism to swing said door.

5 15 10 15 20 25 30 35 40 45 50 55 60

2. The rocket launcher of claim 1 wherein said means engaging said second link comprises a manually actuated operating lever.

3. The rocket launcher of claim 1 wherein said means engaging said second link comprises a cylinder having one end pivoted on said side wall, a piston reciprocable in said cylinder, an operating rod having one end secured to said piston and the other end reciprocable through the other end of said cylinder and engaging said second link, and manually actuated valve means in a hydraulic system selectively operable to pressurize chambers in said cylinder on opposed sides of said piston whereby said breech block is moved to sealed or to open position.

4. In a rocket launcher having a rear wall, there being an opening formed in said rear wall, a breech ring removably fixed to the outer surface of said rear wall about said opening and comprising an inwardly directed reduced portion peripherally engaging the wall of said opening with a tight fit, there being a breech opening formed in said reduced portion having an oblique wall defining a conical seat, an inwardly opening stepped breech block swingable to close said breech opening, said breech block having a first inner portion having a conical peripheral surface to engage an inner portion of said conical seat with a tight fit, a middle portion of slightly reduced diameter forming a first recess, and an outer portion reduced again in diameter to form a second recess of smaller diameter, a brass obturator ring received in said second recess and having a conical peripheral surface to snugly engage the outermost portion of said conical seat, a toroidal resilient obturator pad received in said first recess and having forward and rear flat surfaces tightly abutting contiguous surfaces on said breech block and obturator ring respectively, said obturator pad adapted to engage the middle portion of said conical seat with a gas tight fit, means compressing said obturator pad to effect said gas tight fit comprising, a plurality of circumferentially disposed holes in said breech block in longitudinal alignment with corresponding holes formed in said brass ring, said holes in said breech block having a forward portion of enlarged diameter, a pin received in said aligned holes and having an enlarged head forwardly disposed in said recess of enlarged diameter and a rearwardly threaded portion extending beyond the rear face of said obturator ring for receiving a nut, and a spring in said recess of enlarged diameter extending between said head and the bottom thereof.
